US00D569363S

(12) **United States Design Patent** (10) **Patent No.:** **US D569,363 S**
Lee et al. (45) **Date of Patent:** **** May 20, 2008**

(54) **PORTABLE TELEPHONE**

(75) Inventors: **Hye-Jeong Lee**, Seoul (KR); **Nam-Mi Kim**, Seoul (KR); **Chang-Hwan Hwang**, Seoul (KR)

(73) Assignee: **Samsung Electronics Co., Ltd.**, Suwon, Kyunggi-Do (KR)

(**) Term: **14 Years**

(21) Appl. No.: **29/269,070**

(22) Filed: **Nov. 20, 2006**

(51) **LOC (8) Cl.** **14-03**

(52) **U.S. Cl.** **D14/138**

(58) **Field of Classification Search** D14/137, D14/138, 147, 218, 341-347; D5/1, 6, 16, D5/24, 32, 34, 37-40, 45, 47, 54, 56, 58, D5/66; 455/90.3, 556.1, 556.2, 575.1, 575.3, 455/575.4; 379/433.01-433.13; 361/814; 348/14.02
